ATTORNEY.

UNITED STATES PATENT OFFICE.

SIDNEY O. BIGNEY, OF ATTLEBORO, MASSACHUSETTS.

DESIGN FOR A SAFETY-FOB AND VINAIGRETTE.

40,987.

Specification for Design.

Patented Nov. 15, 1910.

Application filed September 26, 1910. Serial No. 583,979. Term of patent $3\frac{1}{2}$ years.

To all whom it may concern:

Be it known that I, SIDNEY O. BIGNEY, a citizen of the United States, residing at Attleboro, in the county of Bristol and State of Massachusetts, have invented a certain new, original, and ornamental Design for a Safety-Fob and Vinaigrette, of which the following is a specification.

In the accompanying drawings which form a part of this specification, the figure is a front elevation of a safety fob and vinaigrette embodying my new design.

I claim;

The ornamental design for a safety fob and vinaigrette, as shown.

SIDNEY O. BIGNEY.
